[57] **CLAIM**

The ornamental design for a bracket for mounting liquefied petroleum gas tanks, as shown and described.

DESCRIPTION

FIG. 1 is a left side elevational view of a bracket for mounting liquefied petroleum gas tanks showing my new design;

FIG. 2 is a right side elevational view thereof;

FIG. 3 is a front elevational view thereof;

FIG. 4 is a rear elevational view thereof;

FIG. 5 is a top plan view thereof; and

FIG. 6 is a bottom plan view thereof.

The present design is characterized by an ovate overall configuration having a pentagonal lower end, one leg thereof being tangential to the radius of the ovate portion to provide a continuous arc. The open interior of the lower end contrasts with the essentially solid appearance of the major portion.
